(57) **CLAIM**

The ornamental design for a vacuum cleaner with stand and accessories, as shown and described.

DESCRIPTION

FIG. 1 is a perspective view of a vacuum cleaner with stand and accessories showing my new design;

FIG. 2 is another perspective view thereof;
FIG. 3 is another perspective view thereof;
FIG. 4 is a front elevational view thereof;
FIG. 5 is a rear elevational view thereof;
FIG. 6 is a left side elevational view thereof;
FIG. 7 is a right side elevational view thereof;
FIG. 8 is a top plan view thereof;
FIG. 9 is a bottom plan view thereof;
FIG. 10 is an enlarged view of the vacuum cleaner with stand and accessories shown within the area designated as **10** in FIG. 1;
FIG. 11 is an enlarged view of the vacuum cleaner with stand and accessories shown within the area designated as **11** in FIG. 1;
FIG. 12 is an enlarged view of the vacuum cleaner with stand and accessories shown within the area designated as **12** in FIG. 1;
FIG. 13 is an enlarged view of the vacuum cleaner with stand and accessories shown within the area designated as **13** in FIG. 1;
FIG. 14 is an enlarged view of the vacuum cleaner with stand and accessories shown within the area designated as **14** in FIG. 2;
FIG. 15 is an enlarged view of the vacuum cleaner with stand and accessories shown within the area designated as **15** in FIG. 2;
FIG. 16 is an enlarged view of the vacuum cleaner with stand and accessories shown within the area designated as **16** in FIG. 2;
FIG. 17 is an enlarged view of the vacuum cleaner with stand and accessories shown within the area designated as **17** in FIG. 3; and,
FIG. 18 is an enlarged view of the vacuum cleaner with stand and accessories shown within the area designated as **18** in FIG. 3.
The broken lines in the drawings are for the purpose of illustrating portions of the vacuum cleaner with stand and accessories that form no part of the claimed design. The dot-dashed broken lines in FIGS. 1-3 and 10-18 show the boundary of the enlarged view and form no part of the claimed design.

1 Claim, 18 Drawing Sheets
